UNITED STATES PATENT OFFICE.

ERNEST ANSLEY WATSON, OF COVENTRY, ENGLAND, ASSIGNOR, BY MESNE ASSIGNMENTS, TO THE C. L. I. MANUFACTURING COMPANY LIMITED, OF BIRMINGHAM, ENGLAND.

DYNAMO-ELECTRIC MACHINE.

1,319,543.

Specification of Letters Patent. Patented Oct. 21, 1919.

Application filed January 31, 1917. Serial No. 145,697.

To all whom it may concern:

Be it known that I, ERNEST ANSLEY WATSON, a subject of the King of Great Britain and Ireland, residing at Victoria Works, 5 West Orchard, Coventry, in the county of Warwick, England, have invented certain new and useful Improvements Relating to Dynamo-Electric Machines, of which the following is a specification.

10 This invention has for its object to construct an improved dynamo-electric machine for the generation of low tension current for lighting or lighting and starting purposes, and high tension current for ignition 15 purposes, on motor road and other vehicles driven by internal combustion engines, the machine being of the type in which there are combined with the generator field winding, an additional winding serving as a secondary of a high tension ignition system, and a contact mechanism rotating synchronously with the engine for intermittently 20 making and breaking the circuit of the field winding.

25 The invention comprises the provision in the machine of a magnetic shunt or leakage circuit common to the flux of the wound pole and the opposing flux associated with the armature.

30 Referring to the accompanying sheet of explanatory drawings:—

Figure 1 is a cross section; and

Fig. 2 a longitudinal section showing diagrammatically a dynamo constructed in accordance with this invention;

Fig. 3 is a diagram of connections.

In carrying the invention into effect as shown, the ordinary field winding *a* of a low tension generator suitable for lighting or lighting and starting purposes is surrounded by another winding *b* which serves as a secondary of a high tension ignition system. Any suitable mechanism such as that ordinarily employed on magnetos is provided for interrupting the field winding, and such mechanism is rotated synchronously with the engine. The arrangement shown consists of a fixed contact *c* and a movable contact *d*. The latter is mounted on a spring arm *e* actuated by a cam *f* on a wheel *g* driven by a pinion *h* on the shaft *i* of the armature *j*.

For the production of a spark, a comparatively small flux change suffices, provided it occurs with sufficient rapidity. The com-

bination above described would not result in an efficient ignition apparatus because the inductance associated with the armature would tend to resist a rapid change of flux in the field winding. To avoid this it is necessary to produce a magnetic path which is associated with the field winding only and is independent of the armature. Such a path is obtained by the arrangement of an air gap or leakage path or shunt on each side of the pole piece *k* and the adjacent part of the frame *l*. While these paths are not narrow enough to seriously interfere with the flux from the core *m* to the armature, they do insure a definite amount of flux passing from the pole tips to the frame. There are thus two paths for the core flux, one which includes the armature through which the greater part of the core flux passes and a second across the leakage paths or shunts which takes a relatively small amount of the flux. The latter circuit is independent of the armature and consequently the flux associated with it can change with the necessary rapidity to produce a spark in the secondary or high tension current circuit when the current in the field winding is interrupted.

Further in ordinary automobile current generators the demagnetizing magneto-motive-force associated with the armature is usually considerable. The leakage flux due to this magneto-motive-force, or some of it, also crosses the above mentioned leakage paths, but does not enter the core *m* when the winding *a* is energized. When the winding *a* is interrupted, the demagnetizing magneto-motive-force tends to reverse the flux through the main core *m* and hence increases the rapidity of falling of the main flux and therefore assists in the process of flux change necessary for the spark.

In the arrangement shown the core *m* is laminated and formed integrally with a laminated portion *l'* of the frame. This portion is removable and is attached to the solid main portion *l* in any convenient manner. The pole piece *k* is secured to the main portion of the frame by cross bolts *n* of non-magnetic material such as brass and the leakage paths are filled with blocks *o* of non-magnetic material such as brass, these also being secured by the bolts *n*.

Any suitable cut-in and cut-out device is arranged at *p* to prevent discharge of the

battery through the armature *j*, and a switch is provided at *r*. In the diagram at Fig. 3 the battery is indicated by *s*, the sparking plug by *t* and the lamps by *u*. A condenser 5 *v* is provided to suppress sparking at the interrupter of the field winding. High tension current is taken from the winding *b* by a terminal as *w*. Any convenient additional means may be employed in the generator 10 for producing automatic regulation of the current or voltage. Obviously two or more field windings may be used without departing from the invention. When the generator is required to operate as a motor 15 for engine starting purposes any suitable provision is made for temporarily converting the generator into a series motor. For ignition in multi-cylinder engines a distributor is combined with the high tension 20 system of the machine.

The invention is not limited to any particular mechanical details as these may be varied to meet different requirements.

Having thus described my invention what 25 I claim as new and desire to secure by Letters Patent is:—

1. In dynamo electric machines, the combination of an armature, a magnetic frame 30 consisting in part of a solid main portion and a detachable laminated portion, a laminated core formed integrally with said laminated portion of the frame, a pole piece secured to the main portion of the frame and abutting against the said core, said pole 35 piece being spaced from said frame, to provide a magnetic shunt between the ends of the pole piece and the adjacent parts of the

frame, a field winding acting as a primary winding and a secondary winding on the core, an interrupter in the primary winding, 40 and means for actuating the interrupter from the armature, substantially as described.

2. In a dynamo electric machine, a magnetic frame, an armature disposed within 45 the frame at one end thereof, a core carried by the frame at the opposite end thereof, a pole piece carried by the core, said pole piece being spaced from the frame to provide a magnetic shunt, non-magnetic blocks 50 disposed in the space between the pole piece and the frame, and securing means arranged to pass through the frame, the blocks and the pole piece for holding the parts together. 55

3. In a dynamo electric machine, a magnetic frame, an armature disposed within the frame at one end thereof, a core carried by the frame at the opposite end thereof, a pole piece carried by the core, said pole 60 piece being spaced from the frame to provide a magnetic shunt, non-magnetic blocks disposed in the space between the pole piece and the frame, securing means arranged to pass through the frame, the blocks and the 65 pole piece for holding the parts together, a primary field winding on the core, a secondary field winding superposed on said primary winding, an interrupter in the primary winding, and means for actuating the 70 interrupter from the armature.

In testimony whereof I have signed my name to this specification.

ERNEST ANSLEY WATSON.
